Des. 225,911
Patented Jan. 9, 1973

225,911

PARASOL COVER

Mary A. Morgan, 4522 Varble Ave.,
Louisville, Ky. 40211

Filed Apr. 29, 1971, Ser. No. 138,847

Term of patent 14 years

Int. Cl. D3—03

U.S. Cl. D88—3

FIG. 1

FIG. 2

FIG. 3

FIG. 1 is a top plan view of a parasol cover showing my new design with a portion thereof lined for color;

FIG. 2 is a cross-sectional view taken on the line 2—2 of FIG. 1; and

FIG. 3 is a cross-sectional view through the peak of the parasol cover.

I claim:

The ornamental design for a parasol cover, as shown and described.
